(57) **CLAIM**

The ornamental design for a dental unilateral bite block, as shown and described.

DESCRIPTION

FIG. 1 is a perspective view of a dental unilateral bite block showing the new design;

FIG. 2 is a right side elevation view thereof, with the left side elevation view being a mirror image;

FIG. 3 is a front elevation view thereof;

FIG. 4 is a rear elevation view thereof; and

FIG. 5 is a top plan view thereof, with the bottom plan view being a mirror image.

FIG. 6 is a perspective view of another embodiment of a dental unilateral bite block showing the new design;

FIG. 7 is a right side elevation view thereof, with the left side elevation view being a mirror image;

FIG. 8 is a front elevation view thereof;

FIG. 9 is a rear elevation view thereof; and,

FIG. 10 is a top plan view thereof, with the bottom plan view being a mirror image.
